HATBAND

Filed June 21, 1926

Mabel T. Hess,

Inventor

By B. P. Hiborne

Attorney

UNITED STATES PATENT OFFICE.

MABEL T. HESS, OF WICHITA, KANSAS.

HATBAND.

Application filed June 21, 1926. Serial No. 117,422.

My invention relates to improvements in hat bands, particularly hat bands for ladies' hats.

An important object of the invention is to provide a hat band of the above mentioned character, which is adjustable for fitting hats of different sizes and which after adjustment, will securely retain itself within the crown, of the hat.

10 A further object of the invention is to provide a hat band of the above mentioned character which is neat and attractive in appearance, and convenient for use.

Other objects and advantages of the invention will be apparent during the course of the following description.

In the accompanying drawings, forming a part of this specification and in which like numerals are employed to designate like parts throughout the same,

Figure 1 is a plan view of a hat band embodying my invention, showing the same inserted in the crown of a hat,

Figure 2 is an enlarged plan view of a hat band, parts broken away,

Figure 3 is a fragmentary perspective view of a hat band,

Figure 4 is a fragmentary plan view of the same,

20 Figure 5 is a transverse section taken on line 5—5 of Figure 4,

Figure 6 is a similar view taken on line 6—6 of Figure 4,

Figure 7 is a perspective view of one of the prongs carried by the spring element,

Figure 8 is a similar view, showing the inner side of the prong, and,

Figure 9 is a transverse section taken on line 9—9 of Figure 2.

40 In the drawings, wherein for the purpose of illustration, is shown a preferred embodiment of my invention, the numeral 10 designates a hat of any well known or preferred type and 11 is the side wall of the crown of the hat. My improved hat band is designated as a whole by the numeral 12, and is inserted within the crown, as shown.

The hat band embodies normally a flat spring element 13 which is adapted to be bent into a curved or circular formation. Secured to the spring element, preferably at equi-distantly spaced points, are outwardly projecting prongs 14. These prongs are carried by slit-sockets 15, which are adapted to be slid upon the spring element and then clamped thereto. The prongs are secured to

spring element before the fibrous elements of the band are attached to the spring element. One end of the spring element has no prong attached thereto, and this end is 60 adapted to be adjusted longitudinally with relation to the opposite end thereof, carrying the prong.

The band proper comprises an outer tubular casing 16, formed of a strip of fabric 65 which is first placed upon the outer side of the flat spring element, and the prongs 14 project through this strip of fabric. This strip of fabric is then folded longitudinally about the edges of the spring element, and 70 this provides inner flat parallel contacting extensions 17, which are stitched together at 18.

The numeral 19 designates a pad portion, 75 which is formed of a suitable fabric such as velvet, plush, or the like. The pad element is formed of a long strip of this fabric, the edges of which are bent inwardly, as indicated at 20, and 21. The pad element is generally U-shaped in cross section, and the folds in its sides, being of two or more ply, impart to the pad the desired stiffness. The pad element being U-shaped in cross section, it is adapted to receive therein the flat extensions 17, and the sides of the pad element and the extensions 17 are all stitched together by a transverse stitching 22. In this manner the pad element is securely attached to the spring element, and the attaching tubular casing 16, not only encloses the spring 80 element, but provides means for slidably receiving the free end 33 of the spring element, which is adapted to be inserted within the tubular casing 16, inwardly of the opposite end of the spring element.

95 In the use of the band, the free end 33 of the spring element is held within the opposite end of the tubular casing 16, and the band is generally circular. The band may now be introduced into the crown of the hat and circumferentially adjusted therein to fit the same and to cause the prongs 14 to enter the crown. The pad is thereby held securely in place within the crown of the hat.

100 It is to be understood that the form of my invention, herewith shown and described, is to be taken as a preferred example of the same, and that various changes in the shape, size and arrangement of parts may be resorted to without departing from the spirit 105 of my invention, or the scope of the subjoined claim.

Having thus described my invention, I claim:-

A hat band comprising a spring element provided with outwardly projecting prongs, 5 a tubular casing for the spring element including a strip of fabric placed upon the outer side of the spring element and folded about the longitudinal edges of the same for providing inner flat attaching extensions, 10 said attaching extensions being stitched together, and a separate pad element which is generally U-shaped in cross section and formed of a strip of fabric folded longitudinally upon itself to provide the U-shape and 15 having its edges folded upon themselves so

that the side walls of the U-shaped element embody a plurality of plies, said U-shaped pad receiving therein the attaching extensions of the tubular casing and the sides of the U-shaped pad element being stitched to 20 said extensions, the prongs carried by the spring element projecting through the outer side of the tubular casing and the free end of the spring element being adapted to be 25 adjustably inserted within the end of the tubular casing adjacent to the opposite end of said spring element.

In testimony whereof I affix my signature.

MAREL T. HESS.
